UNITED STATES PATENT OFFICE.

WILLIAM LAY, OF KREMLIN, OKLAHOMA TERRITORY.

ROTARY STEAM-ENGINE.

SPECIFICATION forming part of Letters Patent No. 690,164, dated December 31, 1901.

Application filed May 4, 1901. Serial No. 58,807. (No model.)

To all whom it may concern:

Be it known that I, WILLIAM LAY, a citizen of the United States, residing at Kremlin, in the county of Garfield, Oklahoma Territory, have invented new and useful Improvements in Rotary Steam-Engines, of which the following is a specification.

My invention relates to improvements in rotary steam-engines; and the object is to provide a cheap, durable, and efficient machine of the kind named adapted to actuate any desired mechanism associated therewith or connected thereto.

My invention consists in the novel construction of parts and their combination, as will be hereinafter fully described and particularly pointed out and distinctly claimed.

I have fully and clearly illustrated the improvements in the accompanying drawings, wherein—

Figure 1 represents an end elevation of an engine constructed in accordance with my invention. Fig. 2 is a top plan view. Fig. 3 is a vertical transverse section through the engine. Fig. 4 is a transverse horizontal section. Fig. 5 is an inside plan view of the bottom plate of the casing, showing the circular way in which the exhaust-ring is seated. Fig. 6 is an inverted plan view, partly in horizontal section, showing the construction of the piston and the exhaust-ports in the exhaust-ring. Fig. 7 is a perspective view of the exhaust-ring and the exhaust-tubes disposed therein. Fig. 8 is a vertical longitudinal section through a modified form of motor. Fig. 9 is a top plan view of the preferred form of motor arranged to accommodate a vertical piston.

Referring to the drawings, 1 designates the casing, made substantially circular or cylindrical, with an extension 1^a, wherein are located the steamways 9 10, the valve 23, controlling the entrance of steam thereto, and the auxiliary inlet-ports 2 3, opening into the interior of the casing. The interior of the casing is for a distance formed eccentric to the perimeter of the piston, terminating in shoulders 4 5, thus forming enlargement of the steam-space in the piston, as indicated in Fig. 4 of the drawings at 6 7, as will be explained hereinafter. The initial impulse to the piston is given through a central channel or pipe 8, communicating alternately with the casing 1 through the medium of radiating

ports 9 and 10, the inlet-ports 2 and 3 being merely auxiliary ports which assist the expansive force of the steam and are designed for the purpose of providing a secondary impulse to the piston.

11 is a ball-bearing on which the piston 12 rests and has its bearing and is designed for the purpose of reducing the friction thereof within the cylinder.

13 designates a shaft or axle made fast in the hub 13^a of the piston and carrying on its upper end a crown-wheel 14, adapted to mesh with corresponding gear in train with the machinery to be actuated by the engine. The lower end of the shaft 13 is concaved and seated on the ball-bearing 11, as shown in Fig. 3 of the drawings. From the hub 13^a extend radiating arms 15, carrying at their outer ends an inverted-L-shaped flange 16^a, formed with a determined number of recesses or chambers 16 and steam-pockets 31, communicating with said recesses, as shown in Fig. 6 of the drawings. In the bottom plate of the casing is formed a circular depression or way 17, in which is disposed a plate-ring 16^a, formed with exhaust-ports 18^a at determined distances apart, the ring being revolvably seated in the circular way 17, so that as the ports in the plate-ring traverse over the port 20 in the bottom of the casing the steam is discharged in the well-known manner. To revolve the ring 16^a, hollow sleeves 18 or cups 18 are fixed therein in communication with the ports in the ring and placed in the recesses 16 of the piston, so that as the piston rotates it carries with it the ring 16^a, and from time to time the ports are presented over the exhaust-port 20 to discharge the steam. The sleeves or caps 18 are made steam-tight in the recesses of the piston by means of packing-rings 19, as indicated in the drawings.

21 is a suitable base upon which the engine-casing rests, it being understood that the structure above referred to is designed for a horizontal engine; but it is immaterial whether the engine is horizontal or vertical as far as the operation is concerned, as the invention may be utilized in either form of engine.

Suitable forms of packing will be provided at convenient points on the casing and all valves and joints be made steam-tight; but

as these form no part of my invention they will not be described.

In operation, all the parts being assembled, the operator will admit steam into the casing 5 through the medium of the primary duct or port 8 and through one of the branch ports 9 or 10, as may be desired. In Fig. 4 the valve 23 at the juncture of the ports 9 and 10 is turned so as to admit steam to the port 10. 10 Thus the piston will be rotated from left to right. The secondary impulse may be given through the medium of the valve 24 in the pipe leading from the duct 8 to the inlet-port 2. When, however, it is desired to reverse 15 the engine, the valve 23 will be turned so as to admit the motive fluid through the port 9 and the valve 25 will be opened to admit steam through the port 3. The valve 24 will of course then be closed, and the operation 20 of the piston will be from right to left. As the piston rotates and carries the cups with it, the motive fluid will be exhausted therefrom as they pass the exhaust-port 20.

In the modification shown in Figs. 8 and 9, 25 26 designates a casing provided with a single offset 27 at one side thereof and an inlet-port 28, controlled by a suitable valve 29. The construction of the piston is substantially the same as the one described in the preferred 30 form; but this form of engine is particularly applicable to the vertical type. 30 designates the shaft, concentrically arranged with relation to and connected to said piston and on which a suitable fly-wheel may be fixed, as 35 well as a drive-wheel, in the usual manner.

While I have shown the preferred form of my invention, I do not wish to be understood as limiting myself thereto, as I am aware that modifications may be made therein without 40 departing from the spirit or sacrificing any of the advantages thereof, and I therefore reserve the right to make all such changes as fairly fall within the scope of my invention.

Having thus fully described my invention, 45 what I claim as new, and desire to secure by Letters Patent, is—

1. In a rotary engine, the combination of a casing having an exhaust-port, and steam-inlets, a rotary piston in the casing formed 50 with steam-pockets, and a ring rotated by the piston having openings therein to successively register with the exhaust-port whereby the steam is discharged from the steam-pockets of the piston.

55 2. In a rotary engine, the combination of a casing having steam-inlet pipes, a rotary piston in the casing formed with steam-pockets having recesses in their inner wall, a ring in the casing having openings therein, and 60 cups, having passages through them, secured in the ring and disposed in the recesses of the steam-pockets, whereby the ring is revolved and the passages brought successively over the exhaust-port of the casing.

3. In a rotary engine, the combination of 65 a casing having expanding recesses terminating in shoulders, and steam-inlets opening in advance of the shoulders and auxiliary inlets opening behind the shoulders, a revolvable ring, seated in the side plate of the casing, formed with openings to register with the port in the casing and tubular connections engaged by the piston to carry the ring to bring the openings in the ring to register with the exhaust-port in the casing. 70

4. A rotary engine comprising a casing having inlet and outlet ports, and formed with shoulders arranged adjacent the inlet-ports to provide expansion-chambers, a revolvable piston within said casing, a plurality of equidistant cups carried in revolution in the path of the exhaust-port thereby and provided with right-angularly-disposed passages communicating with the exhaust-port and adapted to successively and independently 85 communicate with said exhaust-port.

5. A rotary engine comprising a casing having primary inlet-ports and secondary ports, and a shoulder arranged intermediate the primary inlet-port and the secondary inlet-port to provide an expansion-chamber, a revolvable piston secured within said casing and provided with a plurality of equidistant cups adapted to be carried in revolution by the piston and to successively and independently 95 receive the motive fluid and likewise independently and successively exhaust the same as they pass over the exhaust-port in the casing.

6. A rotary engine comprising a casing, a 100 revolvable piston within said casing having an inverted-L-shaped flange arranged to form a plurality of cups to receive the motive fluid, a ring arranged adjacent said flange, hollow gaskets opening through the ring, said gaskets being adapted to communicate with the exhaust-port and the cup for the purpose described. 105

7. A rotary engine comprising a casing, a primary duct communicating with said casing through the medium of radiating inlet-ports, a valve arranged at the juncture of the inlet-ports and the primary duct, a plurality of secondary inlet-pipes leading from the primary duct to the casing, valves arranged 115 in said pipes, a revolvable piston within said casing provided with a plurality of equidistant cups, a hollow gasket in each of said cups adapted to communicate with the exhaust-port of the casing and means for reversing said piston. 120

In testimony whereof I affix my signature in presence of two witnesses.

WILLIAM LAY.
